SHROUD TO COVER A PORTION OF A BOAT PROPELLER SHAFT AND AN ENTIRE SHAFT BEARING

Robert W. Read, 5405 104th St. SW., Tacoma, Wash. 98499, and David C. Knowlen, Tacoma, Wash.; said Knowlen assignor to said Read

Filed May 1, 1972, Ser. No. 249,472

Term of patent 14 years

Int. Cl. D12—99

U.S. Cl. D12—70

FIG. 1

FIG. 2

FIG. 3

FIG. 4

FIG. 5

FIG. 1 is a perspective view of a shroud to cover a portion of a boat propeller shaft and an entire shaft bearing showing my new design;

FIG. 2 is a side elevational view thereof, the opposite side being the same;

FIG. 3 is a bottom view thereof, the top being a plain flat surface;

FIG. 4 is a front elevational view thereof, and

FIG. 5 is a back elevational view thereof.

We claim:

The ornamental design of a shroud to cover a portion of a boat propeller shaft and an entire shaft bearing, as shown and described.
